R. P. M. DAVIS

MOLD

Filed Oct. 4, 1922

Inventor:

Roy P. M. Davis

By Percy H. Moore
Attorney.

UNITED STATES PATENT OFFICE.

ROY P. M. DAVIS, OF MOUNT UNION, PENNSYLVANIA.

MOLD.

Application filed October 4, 1922. Serial No. 592,224.

To all whom it may concern:

Be it known that ROY P. M. DAVIS, a citizen of the United States of America, residing at Mount Union, in the county of Huntingdon and State of Pennsylvania, has invented certain new and useful Improvements in Molds, of which the following is a specification.

My invention relates to molds for brick making machines.

The principal object of the invention is to provide means for compensating for the wearing away of the projecting edges of the mold and mold partition.

Other and further objects of the invention will be in part described and in part obvious as the description is proceeded with.

In the accompanying drawings forming part of this specification:

Figure 1 is a side elevation of my invention;

Figure 2 is an end view, the trunnions and bearings being omitted.

Figure 3 is a detail view of mold actuating means and

Figure 4 is a top plan view of the mold.

Referring more particularly to the drawings the mold 1, is formed in two parts 2 and 3 which may for convenience be termed the base and upper sections respectively. The base or lower section 2, is provided with ledges or flanges 4, at each end which are embraced by inverted U-shaped yoke members 5, which are bolted to the side plates 7, of the upper section by means of bolts 8 extending through the extended ends of the side plates and through slots 30 in the legs of the member 5. Transverse members or cross heads 9, are bolted to the legs of the members 5, by means of bolts 10, and the two sections are connected together by vertically disposed bolts 11, which pass loosely through the cross heads 9, and through the flanges or ledges 4, lock nuts 12, permitting of the two sections of the mold being adjusted toward or away from each other to vary the thickness of the bricks. Nuts 35 on the lower ends of the bolts 11 support the lower section 2 when the mold is in Figure 1 or upright position.

The lower section 2, is formed with upstanding plungers 13, which project partially into the brick molding compartments 14, of the upper section 3. These plungers receive the charge of mud from any suit-

able source (not shown) and also serve to eject the finished brick.

Bearings 15, are bolted to the inverted U-shaped members by means of bolts 10. These bearings receive and have keyed 60 therein the inner ends of short stub shafts 17 and 18, which in turn are journaled in the mold supporting arms 19 and 20, connected to any suitable support (not shown). The stub shaft 17, has keyed thereon at one 65 end a spoked wheel 22, by means of which wheel the mold support is oscillated at predetermined intervals to dump the molded bricks, a rack bar 23, being employed for this purpose. This rack bar 23, is actuated 70 at predetermined intervals by any suitable means (not shown) to oscillate the mold to inverted or dumping position.

The ejection of the bricks from the mold compartments automatically takes place as 75 the mold supports are oscillated to dumping position. This is caused by the section 2, of the mold support dropping by gravity towards section 1, thereof, it being noted that the section 2, is free to move with the 80 threaded bolts or rods 11, the cross heads 9 serving as guides during this movement. This movement of the section 2, precipitates the plungers 13, through the mold compartments 14, thereby ejecting the brick therefrom, onto the dump table (not shown).

The section 3 comprises the side plates 7 which overlap the guide members 5, and the transverse partitions 27 extending between the plates 7 forming the mold compartments 90 14. The space between the guide members 5 forms a pocket or space 24 in which the partitions 27 seat, the bolts 8, normally resting upon the bottom of recesses 30 and maintaining the upper edges of the side 95 plates 7 and partitions 27 slightly above the top of the guide members 5.

The upper edges of the molds including the partitions 27, are subject to great wear which is compensated for as follows: As 100 wear takes place, the mold is removed, resurfaced to smooth the rough worn edges and then replaced. This wearing and resurfacing reduces the depth of the mold, bringing the top edges of the latter closer to the ends 105 of the plungers. This is then offset by screwing home bolts 28, threadedly mounted in the lugs 29, in the cross heads 9, and arranged to engage with their upper ends the 110 four lower corner edges of the side plates 7

of the mold. If desirable, after the upper edges of one face of the mold becomes worn, the mold can be taken out and reversed, thus preventing an unworn edge above the top 5 of the mold supporting yokes 5. To this end the molds are made of sufficient height to normally project a considerable distance above the top of the mold supporting yokes 5. It will of course, be understood that the 10 resurfacing step may be dispensed with, this step in any event being unnecessary until both edges or surfaces of the mold become badly worn or scarred.

What I claim is:

- 15 1. In a brick making machine, a two part mold comprising a base section and an upper section, mold supporting members between which both of said mold sections seat and are supported for relative movement, 20 and means for adjusting said upper mold section vertically with respect to said supporting members.
2. In a brick making machine, mold supporting members, a two part mold comprising a base section and an open ended reversible upper mold section, both of said sections being supported by said supporting members, and means for adjusting the up-

per section relatively to the said supporting members.

3. In a brick making machine, an open ended mold, means for supporting said mold, adjustable means in said supporting means bearing against the bottom edge of said mold for regulating the height of said mold with respect to said supporting means.

4. In a brick making machine, a two part mold comprising a base and an upper section, said upper section being of open ended skeleton formation and means common to 40 both sections for supporting said sections for relative movement, the said upper section adapted to normally project a considerable distance above said supporting means.

5. In a brick making machine, a pair of 45 inverted U-shaped mold supporting members, an open ended mold seated between said members and projecting thereabove, and means for adjusting the height of said mold with respect to said supporting members.

In testimony whereof I affix my signature in presence of a witness,

ROY P. M. DAVIS.

Witness:

V. L. WALLETT.
